UNITED STATES PATENT OFFICE

2,073,005

MACHINE FOR PRESSING THE BOTTOMS OF SHOES

Andrew Eppler, deceased, late of Lynn, Mass., by
 Ella P. Eppler, executrix, Lynn, Mass., assignor
 to United Shoe Machinery Corporation, Paterson, N. J., a corporation of New Jersey

Application May 11, 1936, Serial No. 79,018
 In Germany February 27, 1936

12 Claims. (Cl. 12—34)

This invention relates to machines for pressing the bottoms of shoes and is herein disclosed in its application to a leveling machine of the so-called automatic type.

5 In one well-known form of leveling machine of the automatic type the leveling operation is performed by relative movement of a leveling tool or roll and a shoe support lengthwise of the shoe and in the leveling operation the roll is automatically controlled with respect to tipping movement about an axis extending lengthwise of the shoe to position it in proper relation to different portions 10 of the bottom of the shoe, means being provided for varying the lengths of the relative movements 15 of the roll and shoe support to accommodate shoes of different sizes and for varying the relation of the shoe support to the roll when the roll is tipped to compensate for variations in the relative lengths of the forepart and shank portions of 20 shoes of different styles. The shoe support comprises a toe rest provided with a rubber pad for engaging the toe end of the shoe and a spindle arranged to engage the heel end of the last in its spindle hole. The spindle is mounted for tipping 25 movements in directions toward and from the toe rest on a heel post which is adjustable toward or from the toe rest to position shoes of different sizes in substantially the same relation to the leveling roll.

30 Such machines are usually provided with spindle-tipping mechanism and with a so-called saddle of leather which is used to transmit the pressure of the roll to the shoe in operating upon certain kinds of work and is mounted for movement into and out of operative position over the 35 bottom of the shoe for use alternatively with the spindle-tipping mechanism to jack the shoe, i. e. to force the toe end of the shoe firmly against the toe rest. When the saddle is used it is applied 40 tightly over the bottom of the shoe by depression of a hand lever, the spindle being tipped somewhat toward the toe rest by the action of the last thereon as the saddle is thus applied and the toe end of the shoe is depressed against the 45 toe rest. In the use of the machine, particularly in operating upon a shoe the bottom of the forepart of which is inclined upwardly and rearwardly from the toe end of the shoe, there is a tendency for the pressure of the leveling roll on 50 that portion of the shoe to displace the shoe rearwardly relatively to the toe rest, thereby varying the relative longitudinal position of the shoe and roll and affecting the action of the roll on the different portions of the shoe bottom. 55 With the saddle applied tightly over the bottom

of the shoe it is desirable that the spindle be locked against tipping movement in a direction away from the toe rest so as to prevent any such displacement of the shoe relatively to the toe rest in the pressure-applying operation.

An object of the invention is to provide improved means for accomplishing that result. For the purpose in view, there is provided, as herein shown, a locking device comprising a member having a series of teeth formed thereon and a pawl arranged to engage some one of the teeth to lock the spindle against tipping movement. More particularly, in the construction shown, the pawl is movable in a direction lengthwise of the series of teeth in response to tipping movement of the spindle toward the toe rest, and means controlled by the above-mentioned hand-lever is provided for moving the pawl into engagement with one of the teeth after the movement of the hand lever to force the saddle against the shoe has been substantially completed. Thus the spindle is permitted to tip toward the toe rest as the saddle is forced against the bottom of the shoe but is locked against reverse tipping movement in the pressure-applying operation. As 20 herein shown, there is provided a roll which is movable with the above-mentioned hand lever and is arranged to engage a rib on the pawl. The rib is curved lengthwise of the series of teeth and is held in engagement with the roll by spring 30 means, the curvature of the rib being such that the pawl is moved into engagement with one of the teeth after the movement of the pawl lengthwise of the series of teeth has been substantially completed. Conveniently, this means is also utilized to render the locking device inoperative by the movement of the saddle out of operative 35 position over the bottom of the shoe. As illustrated, the roll is carried by an arm which is swung in a direction to move the pawl into an inoperative position by the movement of the saddle out of operative position, a latch being provided for holding the pawl in the position into which it has been moved by the movement of the saddle 40 into its idle position.

The above and other features of the invention including various novel details of construction and combinations of parts will now be more particularly described by reference to the accompanying drawing and thereafter pointed out in 50 the claims.

In the drawing,

Fig. 1 is a view in side elevation of a portion of a machine in which the invention is embodied; 55 and

Fig. 2 is a view partly in rear elevation and partly in section of parts of the locking device for the spindle.

Since the invention is illustrated as applied to a leveling machine of a well-known type only such parts of the machine as it is necessary to refer to for an understanding of the invention are shown and will be described in detail. Features of the general organization of machines of this type are disclosed in various prior United States Letters Patent including Letters Patent No. 1,667,761, granted on May 1, 1928 and No. 1,719,158, granted on July 2, 1929, both upon applications of E. E. Winkley and H. A. Davenport. It will be understood that the machine includes an automatically controlled leveling roll 10 and a shoe support or jack which in the power operation of the machine is moved automatically in directions lengthwise of the shoe to cause the roll 10 to operate progressively along the bottom of the shoe. The jack comprises a toe post 12 and a heel post 14 which are pivoted together for relative adjustment for shoes of different sizes by means of a threaded adjusting rod (not shown) which moves the heel post toward or from the toe post so that the toe ends of shoes of different sizes will be presented in substantially the same relation to the roll 10. The jack as a whole is operatively movable about the axis of a shaft 30 (not shown) on which the toe post is mounted, and power-operated means, not herein shown, is provided for imparting to the jack oscillatory movements about this axis to carry the shoe rearwardly and forwardly under the leveling roll. The toe and heel posts are provided with means for supporting a shoe and last for the leveling operation. Mounted on the toe post 12 is a toe rest comprising a block 16 having secured to it a rubber pad 18 for engaging the toe end of the shoe. The heel post 14 at its upper end supports a block 20 carrying a spindle 22 arranged to enter the spindle hole in the heel end of the last. The block 20 is mounted on the heel post for swinging movements about an axis extending laterally of the shoe to permit the spindle to tip in directions toward and from the toe rest. The spindle 22 extends through an enlarged opening in a plate 24 also carried by the block 20, which plate is free to tip about an axis extending laterally of the shoe to adjust itself to the top face of the cone of the last. The block 20 is connected by a link 26 to mechanism which will presently be described whereby the block and spindle may be swung to press the toe end of the shoe firmly down upon the toe rest.

For use in jacking a shoe alternatively with the spindle-tipping mechanism just referred to there is provided as heretofore in machines of the type herein shown a saddle 28 of flexible leather which, as illustrated, is of such length as to cover the entire bottom of the shoe and is connected at the opposite sides of its shank portions by springs 30, one of which is shown in Fig. 1, to the two arms 32 of a bifurcated hand-lever 34 which is utilized to apply the saddle tightly over the bottom of the shoe in the same general manner as illustrated in Letters Patent No. 1,704,822, granted on March 12, 1929 upon an application of H. A. Davenport, one of the arms 32 of the hand-lever 70 being shown in Fig. 1. Each spring 30 at its upper and lower ends engages spiral grooves formed in pins 36, 38 which project respectively from end members 40, 42, each member 40 being pivotally connected to a plate 44 fastened to the saddle 28 and each member 42 being pivotally

connected at 46 to one of the arms 32 of the hand lever 34. To assist in holding the full-length saddle in place there are provided additional springs 48 connected to the opposite sides of the forepart portion of the saddle and to the arms 32 of the hand-lever 34. When the saddle is used the lever 34, the arms of which are pivoted at 50 to blocks slidably mounted in slots 52 on the toe post 12, pulls it down tightly over the shoe and is then locked to a segment 54 on the heel post. The slots 52 are concentric with the pivot about which the heel post is movable toward or from the toe post to permit relative adjustment of the toe and heel posts without disturbing the relation between the hand lever 34 and the heel post 14.

The relation of the lever 34 to the spindle-tilting mechanism will now be described. As fully shown and described in the above-mentioned Letters Patent No. 1,719,158 there is pivotally connected to the lower end of the heel post 14 a link 56 having pivotally connected to its upper end links 58, one of which is shown in Fig. 1. The links 58 extend, one on each side of the heel post 14, toward the toe post 12 and are connected to the arms 32 of the hand lever 34 by short upwardly extending links 60. Depending from the two links 58 are arms 59 connected by a horizontal pin 62 extending through a slot 64 formed in a member 66 connected to the lower end of the link 26 (Figs. 1 and 2). Pivotally connected to the member 66 is a member 68 which may be swung up into position to serve as an abutment for the horizontal pin 62, or down, as shown in Figs. 1 and 2. When the member 68 is in the latter position the pin 62 has free movement in the slot 64 as the lever 34 is swung downwardly so that no motion is imparted to the link 26 in operating the saddle. When the member 68 is in its uppermost position, in which position it is held by the engagement of a spring-pressed pin 70 in the member 66 with a recess 72 in the member 68, downward movement of the lever 34 forces the link 26 downwardly to operate the spindle by engagement of the pin 62 with the member 68. The spindle 22 is normally held tipped toward the toe support by means of a spring 74 extending between one of the links 58 and a pin 76 projecting from the link 26. The mechanism for thus rendering the lever 34 effective to operate either the saddle 28 or the link 26 is substantially the same as that shown and described in the above-mentioned Letters Patent No. 1,719,158.

For purposes of this invention there is secured to the heel post 14 (Fig. 1) a plate 78 having teeth 80 formed thereon which are arranged to be engaged by one or another of a plurality of pawls 82 pivotally mounted upon a pin 84 which connects the member 66 to the link 26. The pawls 82 (Fig. 2) which, as shown, are four in number, are mounted on the pin 84, two on each side of the link 26, which is provided with a plane lower end face held in engagement with a shoulder 86 on the member 66 by the pin 84. The pawls 82, which are preferably of slightly different lengths for better insurance that the link 26 will be locked in whatever position it assumes by tipping of the spindle 22 when the saddle is forced down on the shoe, are urged toward the ratchet teeth 80 by U-shaped springs 88 coiled about the opposite end portions of a bolt 90 carried by the link 26. When the saddle 28 is in position over the bottom of the shoe downward movement of the hand-lever 34 acts

through the springs 30 and 48 to apply the saddle tightly over the bottom of the shoe, the pressure of the saddle on the shoe acting to force the toe end of the shoe into the rubber pad 18 of 5 the toe rest. As the toe end of the shoe is thus firmly seated on the toe rest the spindle 22 and block 20 may be tipped somewhat toward the toe rest by the action of the last thereon, the block 20 being tipped in a direction to move the link 26 and 10 the pawls 82 downwardly, and the construction being such that with the lever 34 locked to the segment 54, the spindle and block are locked against reverse tipping movement from the position into which they have been moved by the 15 last by the engagement of one of the pawls 82 with one of the teeth 80 on the plate 78. Thereafter as the jack is swung in directions lengthwise of the shoe under the roll 10 in the power operation of the machine the shoe and last are 20 held by the spindle 22 against displacement relatively to the toe rest as the pressure of the roll 10 is applied through the saddle 28 to the upwardly inclined bottom face of the forepart of the shoe.

25 For moving the pawls 82 relatively to the plate 78 to release the block 20 and spindle 22 for reverse tipping movement to permit the shoe and last to be removed from the jack after the completion of the pressure-applying operation, the 30 right-hand end pawl 82 (Fig. 2) is provided with a curved rib 92 arranged to be engaged by a roll 94 carried by an arm 96 extending from one of the members 42 (Fig. 1). Projecting from the end pawl 82 is a pin 98 arranged to engage tail portions 100 formed on the remaining three pawls. When the hand lever 34 is unlocked from the segment 54 and swung upwardly to idle position the end pawl is swung away from the plate 78 by the action of the roll 94 on the curved rib 40 92 as the member 42 and the arm 96 move upwardly with the hand lever. It will be evident that as the end pawl is thus swung out of engagement with the teeth 80 on the plate 78 the remaining three pawls are also swung out of engagement with the teeth 80 with the end pawl by 45 engagement of the pin 98 with their tail portions 100. Preferably, as shown, the pin 98 is eccentric so that it may be adjusted to permit the remaining three pawls to assume slightly different positions relatively to the end pawl with one of the pawls in locking engagement with the teeth 80 when the pawls are in the positions shown in Fig. 1. It will be understood that the shape of the curved rib 92 is such that when the hand-lever 34 has been moved into idle position all the 50 pawls 82 will have been moved out of engagement with the teeth 80.

The pivotal connections 46 between the members 42 and the arms 32 of the hand lever 34 55 permit the saddle 28 to be swung either to an idle position at the rear of the heel end of the shoe in which position it is usually draped over the hand lever 34, or to an operative position over the bottom of the shoe, as shown in Fig. 1. As the saddle is swung to its idle position the arm 96 is swung in a direction to cause the roll 94 by engagement with the curved rib 92 of the end pawl 82 to impart a further swinging movement to the pawls 82 in a direction away from the plate 78, this movement of the pawls being limited by the engagement of a shoulder 102 on the above-mentioned end pawl with the shoulder 86 on the member 66. For locking the pawls 82 in their outermost positions there is pivotally 60 connected to the member 66 a latch 104 which

may be swung upwardly into position to engage a shoulder 106 on the end pawl 82. It will be evident that as the end pawl 82 is swung away from the plate 78 by the swinging of the arm 96 in the movement of the saddle into idle position the pin 98 by engagement with the tail portions 100 of the other three pawls will swing them outwardly with the end pawl and will also act to hold them against inward swinging movement relatively to the end pawl with the latch 104 in engagement with the shoulder 106 on the end pawl.

It will be readily seen that with the saddle in its idle position and the pawls 82 held in their outermost positions by the latch 104 the shoe support may be used as heretofore in jacking a shoe after swinging the member 68 upwardly into position to be engaged by the pin 62 in the downward movement of the hand lever 34. When it is desired to use the saddle 28 the latch 104 is 20 swung downwardly into the position shown in Fig. 2 and the saddle 28 is moved into position over the shoe by swinging it forwardly. It will be understood that before the saddle is moved into position over the shoe the operator will 25 mount a shoe and last on the spindle 22 and will swing the spindle 22 and block 20, against the resistance of the spring 74, in a direction away from the toe rest by elevating the toe end of the shoe into position to engage the rubber pad 18 30 on the toe rest. Thereafter with the saddle in position over the bottom of the shoe the hand-lever 34 is swung downwardly to apply the saddle tightly over the shoe and to force the toe end of the shoe firmly against the rubber pad 18. As the 35 hand-lever 34 is swung downwardly the springs 88 act on the pawls 82 to hold the curved rib 92 on the above-mentioned end pawl in engagement by the roll 94. In order to prevent wear of the pawls 82 and teeth 80, the shape of the rib 40 92 is preferably such that the pawls 82 are held out of engagement with the teeth 80 on the plate 78 until after the movement of the hand-lever 34 to force the saddle 28 tightly against the bottom of the shoe has been substantially completed, 45 whereupon one of the pawls 82 becomes effective by engagement with one of the teeth 80 to lock the spindle 22 and block 20 against reverse tipping movement with the hand lever 34 locked to the segment 54. Thereafter, as the hand-lever 34 is swung upwardly to idle position after the completion of the pressure-applying operation, the roll 94 by engagement with the curved rib 92 swings the end pawl and through the pin 98 the other three pawls out of engagement with 50 the teeth 80, the pawls being thus swung substantially at the beginning of the upward movement of the hand-lever 34 by reason of the curvature of the rib 92.

The invention having thus been described, 60 what is claimed as new and what it is desired to secure by Letters Patent of the United States is:

1. In a machine for pressing the bottoms of shoes, the combination with means for applying pressure progressively along the bottom of a 65 shoe on a last, of a shoe support comprising a toe rest and a spindle for engaging the heel end of the last in its spindle hole, said spindle being mounted for tipping movements in directions toward and from said toe rest, a saddle for transmitting the pressure of said pressure-applying means to the shoe, means for forcing the saddle against the bottom of the shoe, and locking means for the spindle, said locking means comprising a member having a series of teeth thereon 70

75

and a member arranged to be moved relatively to said first-named member in a direction lengthwise of said series of teeth in response to tipping movement of said spindle toward said toe rest 5 and to cooperate with one of said teeth to lock the spindle against reverse tipping movement in the pressure-applying operation.

2. In a machine for pressing the bottoms of shoes, the combination with means for applying 10 pressure progressively along the bottom of a shoe on a last, of a shoe support comprising a toe rest and a spindle for engaging the heel end of the last in its spindle hole, said spindle being mounted for tipping movements in directions 15 toward and from said toe rest, a saddle for transmitting the pressure of said pressure-applying means to the shoe, a lever movable to force said saddle against the bottom of the shoe, a locking device arranged to permit the spindle to tip to- 20 ward said toe rest as the saddle is forced against the bottom of the shoe but to lock the spindle against reverse tipping movement in the pressure-applying operation, and means for controlling the time in the movement of said lever when 25 the locking of the spindle takes place.

3. In a machine for pressing the bottoms of shoes, the combination with means for applying 30 pressure progressively along the bottom of a shoe on a last, of a shoe support comprising a toe rest and a spindle for engaging the heel end of the last in its spindle hole, said spindle being mounted for tipping movements in directions toward and from said toe rest, a saddle for transmitting the pressure of said pressure-applying 35 means to the shoe, a lever movable to force said saddle against the bottom of the shoe, locking means for the spindle comprising a member having a series of teeth thereon and a member arranged to cooperate with one of said teeth to lock 40 the spindle against tipping movement, and means controlled by said lever for moving said cooperating member into engagement with one of said teeth after the movement of said lever to force the saddle against the shoe has been substantially 45 completed.

4. In a machine for pressing the bottoms of shoes, the combination with means for applying 50 pressure progressively along the bottom of a shoe on a last, of a shoe support comprising a toe rest and a spindle for engaging the heel end of the last in its spindle hole, said spindle being mounted for tipping movements in directions toward and from said toe rest, a saddle for transmitting the 55 pressure of said pressure-applying means to the shoe, a lever movable to force the saddle against the bottom of the shoe, means for locking said spindle against tipping movement, said means comprising a plate having a series of teeth formed thereon, a pawl arranged to cooperate with some 60 one of said teeth to hold the spindle against tipping movement, said pawl being connected to said spindle for movement in a direction lengthwise of said series of teeth in response to tipping movement of said spindle toward the toe rest, and means controlled by said lever for moving the 65 pawl into locking engagement with one of said teeth after the movement of said pawl lengthwise of said series of teeth has been substantially completed.

70 5. In a machine for pressing the bottoms of shoes, the combination with means for applying 75 pressure progressively along the bottom of a shoe on a last, of a shoe support comprising a toe rest and a spindle for engaging the heel end of the last in its spindle hole, said spindle being mounted

for tipping movements in directions toward and from said toe rest, a saddle for transmitting the pressure of said pressure-applying means to the shoe, a lever for forcing the saddle against the bottom of the shoe, locking means for the spindle comprising a plate having a series of teeth thereon and a pawl arranged by engagement with some one of said teeth to lock the spindle against tipping movement in a direction away from said toe rest, said pawl being movable in a direction lengthwise of said series of teeth in response to tipping movement of said spindle toward said toe rest, spring means for moving the pawl into engagement with one of said teeth, and means for holding said pawl out of engagement with said teeth and for releasing the pawl to the action of said spring means after the movement of the pawl lengthwise of said series of teeth has been substantially completed. 5

6. In a machine for pressing the bottoms of 20 shoes, the combination with means for applying pressure progressively along the bottom of a shoe on a last, of a shoe support comprising a toe rest and a spindle for engaging the heel end of the last in its spindle hole, said spindle being mounted 25 for tipping movements in directions toward and from said toe rest, a saddle for transmitting the pressure of said pressure-applying means to the shoe, a lever for forcing the saddle against the bottom of the shoe, locking means for the spindle 30 comprising a plate having a series of teeth thereon, a pawl connected to said spindle and movable in a direction lengthwise of said series of teeth in response to tipping movement of said spindle toward said toe rest, said pawl having a rib there- 35 on curved lengthwise of said series of teeth, spring means for moving said pawl into engagement with some one of said teeth to lock the spindle against reverse tipping movement in the pressure-applying operation, and a roll movable with said lever 40 and arranged by engagement with said curved rib to hold the pawl out of locking engagement with said teeth until after the movement of said lever to force the saddle against the bottom of the shoe has been substantially completed. 45

7. In a machine for pressing the bottoms of 50 shoes, the combination with means for applying pressure progressively along the bottom of a shoe on a last, of a shoe support comprising a toe rest and a spindle for engaging the heel end of the last in its spindle hole, said spindle being mounted 55 for tipping movements in directions toward and from said toe rest, a saddle for transmitting the pressure of said pressure-applying means to the shoe, a lever mounted for downward and upward swinging movements to force the saddle against the bottom of the shoe and to relieve the pressure of the saddle on the shoe, locking means for the spindle comprising a plate having a series of teeth thereon, a pawl arranged by engagement with some one of said teeth to lock the spindle against 60 tipping movement in a direction away from said toe rest, said pawl being movable in a direction lengthwise of said series of teeth in response to tipping movement of said spindle toward the toe rest, and means for moving said pawl into engagement with one of said teeth near the end of the downward movement of said lever to force the saddle against the shoe and for moving said pawl out of engagement with said tooth substantially at the beginning of the upward movement of said lever to relieve the pressure of the saddle 65 on the shoe. 70

8. In a machine for pressing the bottoms of 75 shoes, the combination with means for applying

pressure progressively along the bottom of a shoe on a last, of a shoe support comprising a toe rest and a spindle for engaging the heel end of the last in its spindle hole, said spindle 5 being mounted for tipping movements in directions toward and from said toe rest, a saddle mounted for movement into and out of operative position over the bottom of the shoe for transmitting the pressure of said pressure-applying 10 means to the shoe, means for forcing the saddle against the bottom of the shoe, locking means for the spindle comprising a member having a series of teeth thereon and a member arranged to cooperate with some one of said teeth to lock 15 the spindle against tipping movement in a direction away from said toe rest, and means for moving said last-named member into an inoperative position by the movement of said saddle out of operative position over the bottom of the shoe. 20 9. In a machine for pressing the bottoms of shoes, the combination with means for applying pressure progressively along the bottom of a shoe on a last, of a shoe support comprising a toe rest and a spindle for engaging the heel end 25 of the last in its spindle hole, said spindle being mounted for tipping movements in directions toward and from said toe rest, a saddle mounted for movement into and out of operative position over the bottom of the shoe for transmitting the 30 pressure of said pressure-applying means to the shoe, means for forcing the saddle against the bottom of the shoe, locking means for the spindle comprising a member having a series of teeth thereon and a member arranged to cooperate with 35 some one of said teeth to lock the spindle against tipping movement in a direction away from said toe rest, means for moving said last-named member into an inoperative position by the movement of said saddle out of operative position over the 40 bottom of the shoe, and means for locking said last-named member in the position into which it has been moved by the movement of the saddle. 10. In a machine for pressing the bottoms of 45 shoes, the combination with means for applying pressure progressively along the bottom of a shoe on a last, of a shoe support comprising a toe rest and a spindle for engaging the heel end of the last in its spindle hole, said spindle being mounted for tipping movements in directions toward 50 and from said toe rest, a saddle mounted for movement into and out of operative position over the bottom of the shoe for transmitting the pressure of the pressure-applying means to the shoe, means for forcing said saddle against the bottom 55 of the shoe, locking means for the spindle comprising a plate having a series of teeth thereon and a pawl connected to said spindle for movement in a direction lengthwise of said series of teeth in response to tipping movement of said

spindle toward said toe rest, said pawl being arranged to cooperate with some one of said teeth to lock the spindle against reverse tipping movement in the pressure-applying operation, and means for moving said pawl relatively to said plate into an inoperative position by the movement of said saddle out of operative position over the bottom of the shoe. 5

11. In a machine for pressing the bottoms of shoes, the combination with means for applying pressure progressively along the bottom of a shoe on a last, of a shoe support comprising a toe rest and a spindle for engaging the heel end of the last in its spindle hole, said spindle being mounted for tipping movements in directions toward and from 10 said toe rest, a saddle for transmitting the pressure of said pressure-applying means to the shoe, a lever movable to force the saddle against the bottom of the shoe, said saddle being pivotally connected to said lever to permit the saddle to be 15 swung into and out of operative position over the bottom of the shoe, locking means for the spindle comprising a member having a series of teeth thereon and a pawl arranged to cooperate with some one of said teeth to lock the spindle against 20 tipping movement in a direction away from said toe rest, said pawl having a rib thereon, and a roll arranged to engage said rib and to swing said pawl into an inoperative position by the 25 movement of said saddle out of operative position over the bottom of the shoe. 30

12. In a machine for pressing the bottoms of shoes, the combination with means for applying pressure progressively along the bottom of a shoe on a last, of a shoe support comprising a toe rest and a spindle for engaging the heel end of the last in its spindle hole, said spindle being mounted for tipping movements in directions toward and from 35 said toe rest, a saddle for transmitting the pressure of said pressure-applying means to the shoe, a lever movable to force the saddle against the bottom of the shoe, said saddle being pivotally connected to said lever to permit the saddle to be 40 swung into and out of operative position over the bottom of the shoe, locking means for the spindle comprising a plate having a series of teeth thereon, a pawl arranged to cooperate with some one of said teeth to lock the spindle against tipping movement in a direction 45 away from said toe rest, said pawl having a rib thereon extending lengthwise of said series of teeth, a roll, spring means for holding said rib in engagement with said roll, and an arm for swinging said roll in a direction to move said pawl into an inoperative position by the movement of 50 said saddle out of operative position over the bottom of the shoe. 55

ELLA P. EPPLER,
Executrix of the Will of Andrew Eppler, Deceased.
